(57) **CLAIM**

The ornamental design for a foot for utility sink, as shown and described.

DESCRIPTION

FIG. 1 is a top perspective view of a foot for utility sink, showing my new design;

FIG. 2 is a bottom perspective view of the foot shown in FIG. 1;

FIG. 3 is a top plan view thereof;

FIG. 4 is a bottom plan view thereof;

FIG. 5 is a rear elevational view; the left side view is a mirror image thereof; and,

FIG. 6 is a front elevational view; the right side view is a mirror image thereof.

The broken lines in the drawings show portions of the foot for utility sink that form no part of the claimed design.
